Fig. 4

Fig. 5

Fig. 6

Fig. 7

Fig. 8

FIG. 1 is a front perspective view of a carrying case cover for a portable sewing machine embodying my new design;

FIG. 2 is a rear perspective view thereof;

FIG. 3 is a left end elevational view;

FIG. 4 is a front elevational view;

FIG. 5 is a top plan view;

FIG. 6 is a rear elevational view;

FIG. 7 is a right end elevational view; and

FIG. 8 is a bottom plan view.

I claim:

The ornamental design for a carrying case cover for a portable sewing machine, as shown.
